CRATE

Irwin E. Schopmeyer, Clermont, Fla., assignor of
one-half to Edgar M. Dilley, Clermont, Fla.

Application January 11, 1938, Serial No. 184,471

1 Claim. (Cl. 220—6)

This invention appertains to new and useful improvements in receptacles of the collapsible type and more particularly to a crate adapted especially for field use such as in the collecting 5 citrus and other fruits.

An important object of the invention is to provide a crate of the character stated which can be collapsed into a small compact form, and which can be stored in a very small space.

10 Other important objects and advantages of the invention will become apparent to the reader of the following specification.

In the drawings:

Figure 1 represents a side elevational view of 15 the crate.

Figure 2 is a vertical sectional view taken substantially on the line 2—2 of Figure 1.

Figure 3 is a sectional view longitudinally and fragmentarily through the crate.

20 Figure 4 is a transverse sectional view.

Figure 5 is a sectional view taken substantially on the line 5—5 of Figure 3.

Figure 6 is a sectional view taken substantially on the line 6—6 of Figure 1.

25 Referring to the drawings wherein like numerals designate like parts, it can be seen that the crate consists of the bottom section 5 having the short upstanding side walls 6 and end walls 7.

Hingedly connected as at 8 to the end wall 7 30 are the end plates 9, while hingedly connected to the upper edges of the side wall 6 as at 10 are the side plates 11, these side plates being provided with inwardly disposed flanges 12 at its ends (see Figure 6) curving inwardly as at 13 for 35 defining channelled forms to receive the rolled ends 14 of the corresponding vertical edges of the end plates 9. As is clearly shown in Figures 1 and 4, swingable latch members 15 are carried by the end plates 9 and are swingable to engage 40 into the vertical slots 16 in the side plates 11 so as to prevent displacement of the rolled ends 14 from the channelled formations at the ends of the side plates 11.

As is clearly shown in Figure 1, the upper ends 45 of the plates 9 are rolled as at 17 to reinforce the same and the upper edge portions of the side plates 11 are bent backwardly as at 18 so as to reinforce the side plates.

Disposed across the bottom 5 is the partition 19 to the upper edge portion of which is hingedly connected the dividing plate 20, which plate is provided with vertical slots 21 adjacent its longitudinal edges for receiving the flange portions 22 of the brackets 23. These flange portions 22 in complement with the corresponding side wall 11 define channels for receiving the rolled edge portions 24 of the dividing plate 20. A swingable latch member 25 is carried by each side plate 11 adjacent the bracket 23 and this latch member has a stop pin 26 below the same to limit its downward movement and is also provided with a lug 26 on its free end for engagement against the corresponding rolled edge 24 of the dividing plate when the dividing plate is to be retained in the vertical position shown in Figure 3.

While the foregoing specification sets forth the invention in specific terms, it is to be understood that numerous changes in the shape, size 20 and materials may be resorted to without departing from the spirit and scope of the invention as claimed hereinafter.

Having described the invention, what is claimed as new is:

A foldable crate comprising a bottom section including short upstanding end and side walls, end and side plates hinged on the end and side walls, rolled portions formed on the end plates, said side plates having portions thereof angularly disposed to form channels to receive the rolled portions and provided with keeper slots adjacent thereto, latches pivoted on the end plates to enter said keeper slots to releasably retain the rolled portions in the channels, a partition hinged on the bottom section and having rolled portions and provided with slots adjacent thereto, angle iron brackets secured on the side plates and entering the last-named slots and securing the rolled portions of the partition therein, angle 30 iron latches pivoted on the side plates and engageable with the rolled portions of the partition to retain said latter-named rolled portions in the angle iron brackets, and stops on the side plates 35 for limiting the pivotal movement of the angle iron latches.

IRWIN E. SCHOPMEYER.
